(57) **CLAIM**

The ornamental design for a monitor, as shown and described.

DESCRIPTION

FIG. 1 is a bottom, front and right side perspective view of a monitor showing my new design;

FIG. 2 is a bottom, rear and left side perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a top, rear and right side perspective view showing the monitor in a first alternate position; and,

FIG. 10 is a bottom, front and left side perspective view showing the monitor in a second alternate position.

The broken lines in the drawings illustrate portions of the monitor which form no part of the claimed design.

The diagonal lines in the drawings represent reflective surfaces.

1 Claim, 10 Drawing Sheets
